UNITED STATES PATENT OFFICE.

NATHANIEL L. BRADLEY, OF WEST MERIDEN, CONNECTICUT, ASSIGNOR TO
BRADLEY & HUBBARD, OF SAME PLACE.

DESIGN FOR A LAMP-PEDESTAL.

Specification forming part of Design No. **7,049**, dated December 16, 1873; application filed November 22, 1873.
[Term of Patent 7 years.]

CASE D.

To all whom it may concern:

Be it known that I, NATHANIEL L. BRADLEY, of West Meriden, in the county of New Haven and State of Connecticut, have invented a new Design for Lamp-Pedestal; and I do hereby declare the following, when taken in connection with the accompanying drawing and the letters of reference marked thereon, to be a full, clear, and exact description of the same, and which said drawing constitutes part of this specification, and represents a perspective view.

This invention relates to a design for a pedestal for supporting a lamp bowl or fountain; and it consists in the peculiar configuration of the pedestal combined with the base and bowl.

A is the base, and B the bowl, either or

both of which may be of any of the known forms of construction, such form not being essential to this design, it only being necessary that a bowl and base be present. On the base stands the figure of a Highlander grasping a staff, and upon the upper end of the staff the bowl B rests, all as shown in the accompanying illustration.

I claim as my invention—

The design for lamp-pedestal, consisting of the figure of a Highlander grasping a staff, upon which rests the lamp-fount, as herein described, and shown in the accompanying illustration.

NATHL. L. BRADLEY.
